ARTICLE CARRYING DEVICE

Oscar A. Herbert, Hollywood, Calif.

Application April 29, 1947, Serial No. 744,579

11 Claims. (Cl. 224—49)

1

My invention relates to and has for a purpose the provision of a simple, inexpensive, practical and durable device designed for the easy carrying by one when walking, of articles of various sizes and shapes, and it is particularly designed for use by school children for carrying books, tablets, and the like to and from school.

My invention embodies a plurality of straps secured one to the other to form a plurality of closed loops arranged to form a sling for receiving the articles to be carried, and means for constricting the sling into firm clamping relation to the articles therein, and which means is operable to retain the sling in constricted form under the weight of the articles when the device is suspended from the hand, arm, or shoulder of the carrier, thus affording an easy convenient and safe means of carrying a plurality of articles and particularly books.

I will describe only three forms of article carrying devices, each embodying my invention, and will then point out the novel features thereof in claims.

In the accompanying drawings:

Fig. 1 is a view showing in perspective one form of article carrying device embodying my invention, as it appears when suspended by the carrier, and with a quantity of books therein.

Fig. 2 is an enlarged transverse sectional view taken on the line 2—2 of Fig. 1.

Fig. 3 is an enlarged fragmentary plan view taken at the point of intersection of the strap loops of the device.

Fig. 4 is an enlarged sectional view taken on the line 4—4 of Fig. 1.

Fig. 5 is a view corresponding to Fig. 2 and showing another form of strap loop constricting and holding means.

Fig. 6 is a sectional view taken on the line 6—6 of Fig. 5.

Fig. 7 is a view similar to Fig. 5 showing a third form of strap loop constricting and holding means.

Fig. 8 is a sectional view taken on the line 8—8 of Fig. 7.

Similar reference characters refers to similar parts in each of the several views.

Referring first to Figs. 1 to 4, my invention in this embodiment is shown as comprising at least two straps S and S1 secured at their ends 15 and 15a, respectively, by means of a bolt 16 or other suitable fastening member (see Fig. 4), such bolt also serving to secure the ends of a third strap S2 to form a closed loop which, while shown of a size to provide a handle by which the device

2

can be suspended from the person while walking, may be increased in size to allow the device to be suspended from the arm or shoulder. Straps S and S1, secured to each other as described, form two closed loops, and by means of stitching 16 (see Fig. 3), the bottom portions 17 and 17a of the straps are secured in right angular intersecting relation to each other, so that the loops, in turn, are secured in corresponding relation, and thus form a sling in which the articles to be carried are received.

In the present instance, I have shown a stack of books B received in the sling so that the loop formed by the strap S has vertical side portions 18 extending from the bottom portion 17 upwardly at the end edges of the books, and converging portions 19 extending upwardly to the secured ends 15. Similarly, the loop formed by the strap S1 has side portions 18a extending upwardly from the bottom portion 17a and at the side edges of the books, and converging portions 19a extending upwardly between the books to the secured ends 15a. As most books, tablets, and even packages are rectangular in form the straps S and S1 are made in different lengths to form loops of different sizes so that the resultant sling, when extended by suspension from the handle strap S2, will properly accommodate rectangular shaped articles, and effectively embrace or clamp them when the sling is properly constructed about the articles and secured in such constricted form by the provision of a similar and effective means which I will now describe.

This sling's constricted and holding means is shown in Figs. 1 and 2 as comprising an element 20 which may be termed a buckle, and members 21 and 21a secured at intervals along the length of the converging strap portions 19 and 19a, respectively, and such members being in the form of round-headed metal studs. The buckle 20 is of disk form and may be made of metal, plastic, or other suitable material, and constructed with a square opening through which the strap portions 19 and 19a extend flatwise as illustrated in Fig. 1.

The studs 21 and 21a are secured to the straps S and S1 so that their heads project from the outer sides of the portions 19 and 19a, in order that one or more studs may engage one edge of the buckle opening 22 on the upper side of the buckle, to secure the latter against sliding movement upwardly on the straps. Where the two straps are of different lengths to form a rectangular sling for articles of rectangular form, the studs on one strap are arranged alternately

with respect to the studs on the other strap so that a finer adjustment of the buckle can be had to hold the sling in constricted form about any number of rectangular articles regardless of the height of the stack formed thereby.

In the use of my device the two strap loops are arranged beneath and about the books B to form the book embracing sling. Then gripping the handle strap S2 and pulling it vertically upward the converging portions 19 and 19a can be extended their full length vertically. With the buckle 20 prepositioned above all of the studs 21 and 21a the user of the device with the other hand can slide the buckle downwardly on the straps, and by tilting it from side to side while so doing, cause the studs to pass upwardly through the buckle 22 until the buckle can be slid no further when, because of the lateral and longitudinal tension placed on the straps, one or more studs is brought into engagement with the upper side of the buckle thus holding the buckle against upward movement on the straps.

In consequence, the buckle and studs coact to secure the loops, and, hence, the sling in constricted form about the books so that the latter can be carried in stacked form against accidental displacement, by merely suspending the sling by the handle strap S2. When so suspended the weight of the books tend to spread the strap portions 19 and 19a outwardly against the walls of the buckle opening 22, thereby maintaining one or more of the studs in firm engagement with the buckle to prevent the latter sliding upwardly and allowing the strap portions to spread and the sling to enlarge and release the books. Even when the sling is not suspended by the handle strap the buckle and studs will maintain the previous adjustment of the buckle to hold the sling in clamping relation to the books, so that when the sling is again suspended from the handle no new adjustment of the buckle is required.

Referring now to Figs. 5 and 6, I have here shown another form of sling constricting and holding means embodying my invention, which comprises a buckle 25 having a square opening 26 therein bounded on its edges by upstanding flanges 27. The buckle holding members are in the form of hooks 28 secured to the strap portions 19 and 19a, and preferably in the same alternate arrangement as the studs 21 and 21a as in the first form of my invention. These hooks are preferably formed of metal and extend downwardly as shown in Fig. 6, so as to engage one of the flanges 27 and thus secure the buckle against upward movement on the straps to hold the sling in constricted position about the articles, once proper adjustment of the buckle has been made to constrict the sling into clamping relation to the books.

Referring now to Figs. 7 and 8 I have shown a third means embodying my invention for constricting the sling and securing it in such constricted position to securely embrace books or other articles placed in the sling. This means comprises a buckle 29, also of disk form and provided with a square central opening 30. Formed integral with the buckle and extending inwardly from the walls of the opening 30 are pointed tongues 31, preferably of V-form. The strap portions 19 and 19a are provided with holes 32 and 32a, respectively, in which one or more of the tongues 31 may be engaged to secure the buckle in adjusted position on the straps and to thereby hold the sling in firm clamping relation

to the articles contained therein. These openings 32 and 32a may be arranged alternately with respect to each other in the same manner as the studs 21 and 21a as in the first form of my invention.

In all forms of my invention the straps may be made of any suitable flexible material such as leather, canvas, or plastic, so long as the requisite flexibility and strength is provided to render the device effective in the carrying of articles, as well as durability.

Likewise, the buckle may be made of metal, plastic, or any other suitable material providing the requisite strength and durability.

Although I have herein shown and described only three forms of article carrying devices, each embodying my invention, it is to be understood that various changes and modifications may be made therein without departing from the spirit of my invention and the spirit and scope of the appended claims.

I claim:

1. An article carrying device, including: a plurality of straps secured to each other to form a sling for the reception of articles to be carried, means supported solely by means of said plurality of straps and operable for constricting the sling into clamping relation to the articles therein, and means fixed on said straps for holding the first mentioned means in sling constricting position so that the articles will be confined in the sling when the device is suspended by the person carrying it.

2. An article carrying device, including: a plurality of straps each secured at its ends to form a loop, and with the ends of all of the straps secured to each other, and the loops secured in intersecting relation to each other to form a sling for the reception of articles to be carried, a member supported solely by means of said straps and being movable on said straps to constrict the sling into clamping relation to the articles therein; and means fixed on said straps engageable with said member for holding the latter in sling constricting position.

3. An article carrying device, including: a plurality of straps each secured at its ends to form a loop, with the ends of all of the straps secured to each other, and the loops secured in intersecting relation to each other to form a sling for the reception of articles to be carried; a buckle slidable on and supported solely by means of said straps for constricting the sling into embracing relation to the articles therein; and elements fixed on said straps coacting with said buckle for securing the latter in sling constricting position.

4. An article carrying device, including: a plurality of straps each secured at its ends to form a loop, with the ends of all of the straps secured to each other, and the loops secured in intersecting relation to each other to form a sling for the reception of articles to be carried; a buckle for constricting said sling into clamping relation to the articles therein, said buckle comprising a plate having an opening therein through which said straps extend; and projections on said straps engageable with the walls of said opening for securing the buckle in sling constricting position.

5. An article carrying device, including: a pair of straps secured to each other to form a pair of intersecting and closed loops, one strap being of greater length than the other to form a larger loop than the other so that the two loops when suspended form a sling for the reception of articles of rectangular form; and means supported

solely by means of said straps and movable thereon for constricting the sling into clamping relation to the articles therein to confine them against displacement and allow the articles to be carried by suspending the device.

6. An article carrying device, including: a pair of straps secured to each other to form a pair of intersecting and closed loops, one strap being of greater length than the other to form a larger loop than the other so that the two loops when suspended form a sling for the reception of articles of rectangular form; a buckle slideable on said straps for constricting the sling into clamping relation to articles therein; and studs on said straps engageable with said buckle for confining the latter in sling constricting position, the studs on one strap being spaced along the length thereof in alternate relation to the studs on the other strap.

7. An article carrying device as embodied in claim 6 wherein a third strap is secured to the first two straps to provide a loop from which the device may be suspended.

8. An article carrying device, including: a pair of straps secured one to the other to provide a pair of intersecting loops; hook members secured to said straps at intervals along the length thereof; and a buckle slideable on said straps to constrict said loops and to be engaged by said members for holding the loops in constricted form.

9. An article carrying device as embodied in claim 8 wherein said buckle has an opening therethrough through which said straps and members are moveable, and flanges bounding said opening to be engaged by said members for securing the buckle against movement upwardly on the straps.

10. An article carrying device, including: a

plurality of straps secured to each other to form a plurality of loops in intersecting relation to form a sling for the reception of articles to be carried; another strap secured to the first mentioned straps by which said loops can be carried in suspended position; means moveable downwardly on the loop straps for constricting the loops into clamping relation to the article therein; and means on the loop straps for locking the first means against upward movement thereon when the device is suspended from said other loop.

11. An article carrying device, including: a pair of straps secured to each other to form a pair of loops one intersecting the other; and means on said straps for constricting the loops into clamping relation to articles to be carried, said means comprising a buckle slideable downwardly on said straps and having pointed projections thereon, and holes in said straps in which said projections are received to secure the buckle against movement upwardly on the straps when the straps are held in suspended position.
